UNITED STATES PATENT OFFICE.

LLOYD V. LEWIS, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

1,217,787.

Specification of Letters Patent. Patented Feb. 27, 1917.

Application filed June 12, 1914, Serial No. 844,864. Renewed February 12, 1916. Serial No. 78,084.

To all whom it may concern:

Be it known that I, LLOYD V. LEWIS, a citizen of the United States, residing in Edgewood Borough, in the county of Allegheny and State of Pennsylvania, have invented certain new and useful Improvements in Railway-Traffic-Controlling Apparatus, of which the following is a specification.

10 My invention relates to railway traffic controlling apparatus.

I will describe one form and arrangement of apparatus embodying my invention, and will then point out the novel features there- 15 of in claims.

In the accompanying drawings, Figure 1 is a view showing in side elevation a portion of a locomotive having applied thereto one form and arrangement of apparatus embodying my invention. Fig. 2 is a view showing on an enlarged scale and partly in section a valve device B shown in Fig. 1. Fig. 3 is a sectional view on the line III of Fig. 2. Fig. 4 is a view showing on an enlarged scale a valve device A shown in Fig. 1.

Similar reference characters refer to similar parts in each of the several views.

Referring first to Fig. 1, 12 designates 30 one of the track rails of a railway upon which a vehicle 13, for example, a locomotive, is adapted to travel. Located in the trackway is a trip 10, and carried on the vehicle 13 is an arm 11 arranged so that 35 it may engage the trip 10 to affect certain apparatus on the vehicle.

As here shown, the trip 10 is stationary, and is therefore always in tripping position, although I do not wish to limit myself to 40 this particular arrangement of trip. The trip, as here shown, is provided with an inclined surface sloping upwardly in the direction of movement of the vehicle 13, and the arm 11 is pivotally mounted at a point 45 15 and is so formed that it may ride upwardly on the inclined surface of the trip 10. The arm is biased by some suitable means so as to be in position for engagement with the inclined surface of the trip 10; 50 as here shown, this bias is obtained by means of a helical spring 14 which surrounds a rod 16. The lower end of rod 16 is provided with a jaw 17 which is pinned to the

arm 11, while the upper end of rod 16 passes through a lug 18 formed on a bracket 55 19 which is mounted on a part of the under frame of the vehicle, here shown as being the bumper beam 21. The lower end of spring 14 bears against the jaw 17, and the upper end against the lug 18. The 60 pressure of the spring 14 on the jaw 17, and the vertical location of arm 11, may be adjusted by means of a nut 20, screwed on the upper end of rod 16 and bearing on the top of lug 18.

Mounted on the locomotive is a box 22 which incloses certain controlling apparatus which I will now describe. Mounted in this box is a block 27 having a hole 34, through which passes a rod 30. The lower end of this rod carries a jaw 32, which is pinned to the arm 11, and the upper end is provided with a head in the form of a nut 31, which rests normally on the upper surface of the block 27.

A latch 36 is pivotally mounted at point 37 on block 27 and is biased by means of a spring 38 to the position in which it is shown in Fig. 1. This latch is provided with a shoulder 39 which lies in the path of the nut 31, so that when the arm 11 is raised by trip 10, the nut 31 engages the shoulder 39 and swings the latch 36 laterally against the action of spring 38. I utilize the lateral movement of the latch 36 to control a valve device A which is shown more clearly in Fig. 4 and which opens and closes a pipe 41.

Referring to Fig. 4, the valve device A comprises a body 44, a cap 45, and a head 46, all held together by bolts 47. A valve stem 43 passes through a hole in the head 46 and is provided with a flange 48 which limits the outward movement of the stem by engaging the head 46. This stem 43 is adapted to be pressed inwardly by latch 36 (see Fig. 1) when arm 11 is raised. The body 44 is provided with an annular valve seat 49 upon which a valve 50 is adapted to be seated. This valve 50 is held against its valve seat by a spring 54. The valve 50 is screwed on the end of a longitudinally grooved stem 51. A piston 52 is adapted to reciprocate in the cylinder formed by the body portion 44. This piston carries an extended sleeve 53 which surrounds the stem

51 and serves as a guide therefor. The end of the sleeve 53 rests against a washer 92, which in turn rests against the valve 50. Pipe 41 opens into chamber 55 and the body 44 is provided with a port 56 by which the chamber 55 is opened into atmosphere when piston 52 moves to the left, the port 56 being so located that a considerable movement of piston 52 is necessary in order to exhaust chamber 57 through port 56 to atmosphere.

10 The body 44 is provided with another port 118, for exhausting to atmosphere any fluid which may leak past valve 50 into chamber 126 on the left-hand side of piston 52.

15 The operation of the valve device A is as follows: Under normal conditions the valve 50 rests against its seat 49, being held there both by spring 54 and by the pressure on the valve of the fluid in chamber 55. When 20 the valve stem 43 is pressed inwardly by latch 36, the head 48 engages the end of stem 51 and moves valve 50 from its seat. Fluid pressure then flows from chamber 55 through the sleeve 53 into chamber 57, and the fluid 25 pressure in chamber 57 acting upon the right-hand face of piston 52 will move piston 52 to the left until the prongs on sleeve 53 engage valve 50. If now the pressure in chambers 55 and 57 acting upon piston 52 is sufficient 30 to overcome the pressure of spring 54, the piston will move still farther to the left until it seats upon gasket 127, thereby fully opening the port 56 so that the fluid pressure will be rapidly exhausted to atmosphere.

35 This fluid pressure in chambers 55 and 57 acting against the area of stem 43, moves stem 43 to the right, and leakage past stem 43 is then prevented by the pressure of head 48 against cap 46. The area of piston 52 is 40 comparatively large, hence only a comparatively small fluid pressure upon piston 52 is required to equal the pressure of spring 54. As soon as the pressure upon the piston 52, decreases to a value less than the pressure 45 of spring 54, the piston 52 will tend to return, thereby partially closing orifice 56. This throttling of orifice 56 has the effect 50 of increasing the pressure in chamber 57 so that a point of equilibrium is soon reached at which the pressure against piston 52 just balances the pressure of spring 54. Then in order to move piston 52 to its extreme right-hand position, it is necessary to further reduce the pressure in chambers 55 and 57, 55 which may be done, for example, by temporarily disconnecting pipe 41 from its source of fluid pressure.

60 Mounted also in the box 22 is a valve device B which, in conjunction with valve device A, controls the fluid pressure in a pipe 109 which may be connected with the brake pipe of the vehicle or may be employed otherwise to control the brakes of the vehicle.

65 Referring now to Figs. 2 and 3, the valve de-

vice B comprises a casing formed of three sections 60, 61, 62. The section 61 contains a chamber 64, into which opens a pipe 58 which is connected with a suitable source of fluid pressure such as the main reservoir of the vehicle. Mounted in the chamber 64 is a slide valve 65 which slides over ports 69, 70 and 71 in a wall of the chamber. Ports 71 and 70 are connected respectively to the air brake control pipe 109, and to the pipe 75 41, and port 69 is open to atmosphere. The slide valve is reciprocated by shoulders 67 and 67^a on an extension 66 of a piston 68. This piston is adapted to reciprocate in a cylinder formed in section 61 of the casing. The shoulder 67 is shaped to fit the chamber 64, and, therefore, serves as guide to constrain the piston 68 to movement parallel to its cylinder; this shoulder is triangular in shape or is otherwise recessed to permit the 85 passage of fluid from one side to the other thereof. The slide valve 65 is held against its seat by a spring 72 which slides along the wall of the chamber 64 opposing the slide valve seat and which presses upon a pin 131 90 mounted in the slide valve. A reservoir 73 adapted to retain fluid pressure is screwed into the section 62 of the device. This reservoir is open at its top so that it communicates with section 62, and the pressure in the reservoir acts upon the bottom of a piston 74 which is adapted to reciprocate in a cylinder formed in section 60. The area of this piston 74 is greater than the area of piston 68. Piston 74 is fixed to a stem, the upper end of which may reciprocate in a suitable socket 78 in piston 68. The function of stem 76 is to raise piston 68 when piston 74 is raised by fluid pressure in reservoir 73. A helical spring 77 extends from piston 74 105 to piston 68, and tends to separate these two pistons. A valve body 107 is screwed into the upper section 61 of the device, and into this valve body is screwed an iron-clad electromagnet 79 which controls a pin valve 80. 110 This pin valve connects the reservoir 73, through a pipe 81, with atmosphere or with chamber 64, according as the electromagnet is deenergized or energized. The pipe 81 is provided with an orifice 86 of restricted area. 115 A pipe 83 opens into the chamber 83 between pistons 68 and 74. This pipe may be connected with atmosphere or with pipe 58 by means of a cock 84 (see Fig. 1). The purpose of this cock is to cut the entire apparatus out of service as hereinafter explained.

120 The operation of this valve device B is as follows: Chamber 64 is constantly filled with fluid pressure from pipe 58. This fluid pressure acts upon the upper face of piston 68 and holds the latter down against its seat 75, thereby holding slide valve 65 in the position shown. When magnet 79 is deenergized, reservoir 73 is connected with atmos- 130

phere by the pin valve 80, as shown in the drawing. When magnet 79 is energized, it operates pin valve 80 to disconnect the reservoir 73 from atmosphere and connect it with chamber 64. When the pressure in reservoir 73 reaches a certain proportion of the pressure in chamber 64, its action on piston 74 is sufficient to overcome the pressure on piston 68, so that the latter is unseated, thereby 5 exhausting the small annular chamber 99 to atmosphere through cock 84. The pressure of air on the top of piston 68 now acts on a smaller area of this piston, so that a force sufficient to start this piston from its 10 seat will be sufficient to overcome the added friction of the slide valve and to quickly 15 complete the stroke of the pistons and slide valve. Quick action of the slide valve is thereby secured.

20 The period of time required for the pressure in reservoir 73 to reach this proportion of the initial pressure depends upon the capacity of the reservoir 73 and upon the area of orifice 86; hence, this period of time may 25 be varied by varying either one or both of these values.

When it is desired to cut the apparatus out of service, that is, to permanently disconnect pipe 41 from the air-brake control pipe 109, 30 the handle of cock 84 is turned from the position shown in full lines to the position shown in dash lines, thereby connecting chamber 85 with pipe 58. Both faces of piston 68 are then subjected to fluid under the 35 same pressure, and the spring 77 then becomes effective to raise the piston 68 away from stem 76, thereby moving the slide valve 65 to such position as to disconnect pipe 41 from the air-brake control pipe 109.

40 It will be seen from an inspection of Fig. 1 that the two valve devices A and B are in series as to their control of brake pipe 109, that is, it is necessary that both of these 45 valve devices be open to cause an application of the brakes. Valve B is normally open, and valve A is opened by every trip 10, hence, unless valve B is closed just before each trip 10 is reached, the brakes will be applied at each trip. The closure of valve B 50 is only accomplished when the speed of the vehicle is at or below the predetermined speed at the trip, this control of valve B being secured by means which I will now explain.

55 A contact shoe 103 is mounted on a beam 104 carried by the vehicle, and is connected with one terminal of magnet 79 by a wire 105. The other terminal of magnet 79 is connected with the locomotive frame by wire 60 106. Extending in the rear of the trip 10 a predetermined distance, is a ramp rail with which the shoe 103 is adapted to make contact. As here shown, this ramp rail comprises two sections 101 and 102 insulated 65 from each other. 100 is a source of current

one terminal of which is constantly connected with section 102 of the ramp rail by wire 111. The other section 101 of the ramp rail is connected with or disconnected from the last-mentioned terminal of the source 100 70 according as a circuit controller 109 is closed or open. This circuit controller 109 may be operated by any suitable means, such for example, as by a railway signal. The other terminal of source 100 is connected with 75 track rail 12 by a wire 110.

The operation of the apparatus is as follows: Assume that the vehicle 13 is traveling in the direction indicated by the arrow, and that the circuit controller 109 is open, as 80 shown in the drawing, then when contact shoe 103 engages section 101 of the ramp rail, the circuit for magnet 79 is not closed because section 101 is not connected with the source of current 100. When, however, 85 the contact shoe 103 reaches section 102 of the ramp rail, the following circuit for magnet 79 is closed: from source 100, through wire 111, section 102 of the ramp rail, contact shoe 103, wire 105, magnet 79, wire 106, 90 locomotive frame, track rail 12, wire 110 to source 100. The energization of magnet 79 operates the pin valve 80 to admit fluid pressure to the reservoir 73, and if the speed of the vehicle 13 is such that the slide valve 95 65 is operated in time to disconnect pipe 41 from the air-brake control pipe before trip arm 11 strikes trip 10, the brakes will not be applied although valve A will be opened by latch 36 as hereinbefore explained. If, however, the speed of the vehicle is such that slide valve 65 is not moved in time to disconnect pipe 41 from the air-brake control pipe before valve A is opened, the brakes 100 will be applied. If the circuit controller 109 105 is closed, it will be clear that magnet 79 will be energized as soon as contact shoe 103 engages section 101 of the ramp rail and that a correspondingly higher speed of the vehicle 110 is permissible without application of the brakes being caused.

Although I have herein shown only one form of apparatus embodying my invention, it is understood that various changes and modifications may be made therein within 115 the scope of the appended claims without departing from the spirit and scope of my invention.

Having thus described my invention, what I claim is:

1. In combination, a railway vehicle, vehicle-controlling apparatus thereon comprising two valves connected in series, one of said valves being normally closed and the other normally open, means located in the 120 trackway for opening said normally closed valve, time-controlled means on the vehicle for closing said normally open valve, and means located in the trackway for setting said time-controlled means into operation at 125 130

a predetermined distance in the rear of the point at which the normally closed valve is opened.

2. In combination, a railway track, a vehicle adapted to travel thereon, a brake controlling pipe on said vehicle, two valves in series in said pipe one of which is normally closed and the other normally open, a trip on the trackway, means on the vehicle adapted to coact with said trip to open the normally closed valve, time controlled means on the vehicle for closing said normally open valve, a ramp rail extending a predetermined distance in the rear of said trip and divided into sections, electrically isolated from each other, means for energizing each section of said conductor, a second device carried by the car or train adapted to coact with the conductor, and means carried by the car or train for setting the time-controlled means into operation when said second de-

vice coacts with a section of the conductor which is energized.

3. In combination, a railway track, a vehicle adapted to travel thereon, a brake controlling pipe on said vehicle, two valves in series in said pipe one of which is normally closed and the other normally open, a trip on the trackway, means on the vehicle adapted to coact with said trip to open the normally closed valve, time-controlled means on the vehicle for closing said normally open valve, and means located in the trackway for setting said time-controlled means into operation at a predetermined distance in the rear of said trip.

In testimony whereof I affix my signature in presence of two witnesses.

LLOYD V. LEWIS.
